CLAIM

The ornamental design for a combined slant marker and base, substantially as shown.

DESCRIPTION

FIG. 1 is a perspective view of the combined slant marker and base showing my new design;

FIG. 2 is a front elevational view thereof;

FIG. 3 is an end elevational view thereof as viewed from the right in FIG. 2, the other end being a mirror image thereof; and

FIG. 4 is a rear elevational view thereof.
